UNITED STATES PATENT OFFICE.

SVEN T. NELSON, OF CHICAGO, ILLINOIS, ASSIGNOR TO SULLIVAN MACHINERY COMPANY, OF CHICAGO, ILLINOIS, A CORPORATION.

HOISTING-ENGINE.

No. 826,956.

Specification of Letters Patent.

Patented July 24, 1906.

Application filed March 31, 1906. Serial No. 309,022.

To all whom it may concern:

Be it known that I, SVEN T. NELSON, a citizen of the United States, and a resident of Chicago, county of Cook, and State of Illinois, have invented certain new and useful improvements in Hoisting-Engines, of which the following is declared to be a full, clear, and exact description.

The invention relates to hoisting-engines, such as are usually employed for operating the cages or "skips" in the shafts of mines, and the improvement seeks to provide safety mechanism for automatically cutting off or throttling the supply of motor fluid to the engine before the cage reaches the end of its travel in the mine-shaft, so that suitable brake mechanism may be subsequently applied either automatically or by hand to arrest the movement of the engine and cage.

A further object of the invention is to provide shifter mechanisms for cutting off the supply of motor fluid and applying the brake, together with means driven from the engine for automatically operating said shifter mechanisms to close the throttle and apply the brake successively at predetermined points as the cage approaches the end of its movement. In this way accidents due to overrunning the cage are prevented, even though the engineer may be careless or inattentive and even though his hand controlling-gear may be out of order.

The invention also provides, in connection with the automatic throttling mechanism, suitable reversing means connected thereto, so as to release or restore the throttling mechanism and permit the operation of the engine in reverse direction.

The improvement also provides a by-pass around the throttle, so that a small amount of steam or motor fluid may be admitted to the engine after the operation of the automatic mechanism.

With these and other objects in view the invention consists in the features of construction, combinations, and arrangements of parts hereinafter set forth, illustrated in the accompanying drawings, and more particularly pointed out in the appended claims.

In the drawings, Figure 1 is a side elevation of a hoisting-engine with the improved controlling mechanisms applied thereto. In this figure the parts are shown in section on line 1 1 of Fig. 2. Fig. 2 is a plan view with

certain parts broken away. Fig. 3 is a view 55 in elevation of the automatic operating-gear ing for the brake and throttle-valve shifter mechanisms, parts being shown in section on line 3 3 of Fig. 2. Fig. 4 is a plan view of parts of the operating mechanism and the 60 brake-shifter shown in Fig. 3. Figs. 5 and 6 are elevation and plan views, respectively, of the brake-shifter mechanism or engine. Fig. 7 is a view in elevation of the throttle-valve shifter mechanism and its actuating means. 65 Fig. 8 is a plan view of parts shown in Fig. 7. Figs. 9 and 10 are views in elevation of parts shown in Figs. 7 and 8 with certain parts in section on lines 9 9 and 10 10 of Figs. 7 and 8, respectively. Fig. 11 is a detail view of a 70 part of the shifter-actuating means shown in section on lines 11 11 of Figs. 7 and 12. Fig. 12 is a detail view with parts in section on line 12 12 of Fig. 11. Fig. 13 is a view in elevation of a portion of the reversing-gear with 75 parts shown in section on line 13 13 of Figs. 2 and 14. Fig. 14 is a sectional view of the reverse mechanism or engine. Fig. 15 is a side view of the reverse-engine with the outer cap-plate removed and parts shown in sec- 80 tion on line 15 15 of Fig. 14. Fig. 16 is a detail view in elevation with parts shown in section on lines 16 16 of Figs. 2 and 17. Fig. 17 is a plan view of parts shown in Fig. 16. Fig. 18 is a detail view in elevation of parts 85 shown in section on line 18 18 of Fig. 17.

The hoisting-engine here shown is of the single-drum type for operating two cages in the mine-shaft, the cages being connected to cables wound in opposite directions upon the 90 engine-drum, so that they are hoisted "in balance"—that is to say, one car is raised and the other is lowered. The present improvements may readily be applied to other types of hoisting-engines.

In the form shown the drum A (see Figs. 1 and 2) is mounted upon and fixed to the engine or drum-shaft a. Two engines (only one of which is shown) are provided, one being coupled to each end of the drum-shaft a. 100 Each end of this shaft is journaled in a suitable bearing 10 at the forward end of the engine-frame 11, that is mounted upon a suitable foundation 12 at one side of a central pit. Each end of the shaft a is provided 105 with a crank 13, coupled to the connecting-rod 14 of the adjacent engine. The engine-cylinder 15 is shown as provided with the or-

inary Corliss valve-gear driven from a wrist-plate 16. The latter is operated from the valve-shaft 17, that extends from side to side in front of the drum A and is provided on either end with a crank-arm 18, to which a link 19 is connected. Link 19 operates a rocker-arm 20, and the latter in turn is connected to operate the wrist-plate by a link 21. The valve-shaft is provided with a gear 22, driven from the gear 23 on the engine-shaft through the medium of an intermediate idler 24. Shaft 17 is connected to gear 22 in a manner permitting the reversal of the engine, as hereinafter described.

15 The throttle-valve B on the engine-cylinder 15 may be of any suitable construction. In the form shown the throttle-valve casing is provided with an inlet-elbow 25, that communicates at its lower end (see Fig. 16) with 20 a flattened pipe or passage 26, extending upwardly through the cylinder-jacketing. At its lower end pipe 26 communicates with an elbow 27, leading from the steam-supply pipe 28. A throttle-valve shaft *b* (see Figs. 1, 2, 16, and 17) is mounted in suitable bearings 29 and 30 on the elbow 27 and on a bed-plate C' in the central pit. The throttle-valve shaft *b* is centrally provided with a crank-arm 31, connected by a rod 32 to a 30 suitable hand-lever on the engineer's platform C. This platform (shown in full lines in Fig. 1 and in dotted lines in Fig. 2) is mounted upon pillars 33, rising from the floor of the pit. At each end the throttle-shaft is provided with a crank-arm 34, that is connected by a rod 35 to a crank-arm 36 upon the inner end of a short shaft 37. This shaft is journaled in suitable brackets upon the top of the engine-cylinder and is provided 40 centrally opposite the throttle-valve with a crank-arm 38, connected by a rod 39 to one end of a link 40. The other end of the link is connected to the upper end of the stem 41 of the throttle-valve. Link 40 is pivoted at its 45 upper end to a swinging arm 42, that is journaled at its lower end upon the top of the throttle-valve casing, the arrangement being such that a straight-line movement is given to the upper end of the throttle-valve. By 50 the connection described the throttle-valve may be opened and closed from the engineer's platform.

The automatic shifting mechanism for the throttle (see Figs. 2, 7, 8, 9, and 10) is mounted upon a bed-plate 43 upon the floor and at one side of the central pit. As two cars are operated by the engine-drum A, one of which moves up as the other is lowered, means are provided for throttling the engine when either 60 car approaches the surface. Two shafts *d* are journaled in suitable end brackets 44 and 45 upon the bed-plate 43 and are also preferably journaled intermediate their ends in brackets 46 on the base-plate 43. At their 65 inner ends these shafts are provided with a

pair of bell levers or arms 47 and 48, (see Fig. 9,) that are fixed to the shafts and connected at their upper ends by a spring 49. This spring normally holds the arms inwardly toward each other against a pair of adjustable stop-screws 50, that are adjustably threaded through lugs 51 upon the end bracket 44. The other arms of the bell-levers are connected by links 52 to the ends of a rocker-arm 53, that is centrally pivoted or journaled upon the end bracket 44. The bell-lever 47 is provided with a projecting-arm 54, that is connected to suitable means for shifting the throttle-shaft to close the throttles, as herein-after described. The arrangement is such 80 that when either of the arms 47 or 48 is moved outwardly away from the stop 50 the other arm will also be moved outwardly and the arm 54 will be drawn down to operate the throttling mechanism.

For moving the shafts *d* and arms 47 and 48 thereon each shaft is provided with a suitable shifter, which are shown in the form of U-shaped brackets D. These shifters or brackets D are keyed upon the shafts *d*, 90 but are preferably longitudinally adjustable thereon, being held in adjusted position by set-screws 55. An actuator for the shifters in the form shown comprises a cylindrical cam member E, mounted upon a screw-shaft *e*. The cam member E is keyed to the screw-shaft to rotate therewith, but does not mesh with its threads. This screw-shaft is journaled in the upper ends of a pair of arms 56, that are mounted upon and keyed to a 100 rock-shaft *f*. This shaft is journaled in the end brackets 44 and 45 between the shafts *d* and at its inner end in a bracket 57, arranged centrally on the floor of the pit. (See Fig. 2.) At its inner end the shaft is provided with a crank-arm 58, connected by a rod 59 (see Fig. 1) to a hand-lever upon the engineer's platform. By rocking the shaft *f* the arms 56, screw-shaft *e*, and actuating cam member E may be shifted from one side to 110 the other.

Screw-shaft *e* is continuously driven from the engine-shaft by suitable reducing-gearing. In the form shown the shaft is provided on its end (see Fig. 7) with a gear 60, meshing 115 with a gear 61, mounted loosely upon the rock-shaft *f* inside of the end bracket 45. Gear 61 is provided with a sleeve 62, extending around the shaft *f* and through the bracket 45, and a beveled gear 63 is fixed to the outer 120 end of the sleeve. Gear 63 meshes with a beveled gear 64 upon the lower end of an upright shaft 65, that is journaled in an overhanging lug upon the end bracket 45 and in a bracket 65' upon the upper inner edge of 125 the engine foundation 12. (See Figs. 1, 3, and 7.) A horizontal shaft 66 (see Fig. 3) extends above the upper inner edge of the engine foundation 12 and is journaled at its 130 ends in suitable brackets 67 and 68. At one

end the shaft is provided with a beveled pinion 69, meshing with a beveled gear 70 upon the upper end of the vertical shaft 65. At its opposite end (see Figs. 2 and 3) shaft 66 is connected by beveled gears 71 to a short stud-shaft 72, that carries a spur-gear 73, meshing with a spur-gear 74 upon the engine-shaft. By this means the screw-shaft *e* is slowly rotated in either of its positions and in one or the other direction as the engine-shaft is driven.

The cam-actuating member *E* is, as stated, keyed to the screw-shaft *e* and rotates therewith in one or the other direction. This cam member is also fed along the shaft by a nut 75. (See Figs. 11 and 12.) This nut is mounted within and held against rotation by a supporting-block formed of separate sections 76 and 77 suitably bolted together. The section 76 of the nut-block is provided with a depending portion 78, that engages and is guided upon the rock-shaft *f*. The section 77 of the nut is provided with a semicircular inwardly-extending or hook-shaped lip or flange 79, (see Figs. 7 and 12,) that engages an annular flange 80 upon the end of the hub-portion of the actuating cam member *E*. This cam member thus rotates and shifts longitudinally in one or the other direction, in accordance with the direction in which the engine is running. The longitudinal movement of the actuator *E* is of course proportional to the speed of the car.

The shifters or brackets *D* are provided at their upper ends with rollers 81, mounted on shafts or spindles 82, extending between the arms of the brackets. The shifters *D* will be mounted upon the shafts *d*, but at opposite ends thereof and adjacent the ends of the longitudinal path of travel of the cam-actuating member *E*. The latter is provided on its ends with spiral cam-surfaces 83, arranged to engage the rollers 81 to operate the shifters *D* and rock-shafts *d*.

The rock-shaft *f*, which may be operated by the engineer to shift the screw *e* and actuating member *E* transversely from side to side, is also connected to control the operation of the reverse mechanism for the engine. The bodily-transverse shift of the screw *e* by the movement of the reverse-shaft *f* will move the actuating cam member *E* out of line with one of the shifter-rollers 81 and into line with the other roller. At the same time the reverse-gear is operated to change the direction of travel of the engine. The actuating cam member *E* is always in line with one of the shifter-rollers 81, and the gearing is such that it will travel toward the shifter-roller with which it is in line. These rollers are yieldingly pressed by springs 84, coiled about the spindles 82, toward the actuating member *E*, so that the rollers will yield longitudinally when engaged by the actuating member if the spiral cam-surfaces 83 on the

ends thereof do not properly mesh with the rollers.

In operation the shifters *D* will be adjusted to such position on the shafts *d* that one of the rollers will be engaged by the actuating cam member *E* when one or the other of the cages of the hoist approaches the upper end of the mine-shaft. When this occurs, the engaged roller 81 will be pressed outwardly by the spiral cam-surface 83 until it rides upon the cylindrical surface of the cam member. Such movement of either rollers will shift the rock-arms 47 and 48 on the shafts *d* outwardly and move the arm 54 down to close the throttle-valves. The engineer cannot then open the throttles until he has first operated rock-shaft *f* to reverse the engine. This movement will throw the cam member *E* transversely away from the engaged roller, so that spring 49 may draw the rock-arms 47 and 48 inwardly back to normal position against the stop-screws 50, and the throttle-valve-controlling arm 54 is raised to normal position.

The throttle-valve-controlling arm 54 may, if desired, be connected directly to the throttle-operating mechanism; but with a large engine this arm preferably controls a small auxiliary engine, which in turn closes the throttle-valve. For this purpose the controlling-arm 54 is connected by a rod 85 to a rock-arm 86 upon a short shaft 87. This shaft is journaled upon a bracket 88 upon a small engine-cylinder *G*, and a short rock-arm 89 on the shaft is connected by links 90 to the valve-rod 91 of the throttling-engine. This engine is mounted upon a suitable I-beam frame 92, and its piston-rod *g* operates a cross-head 93, (see Figs. 1 and 2,) to which a pair of links 94 are connected. A rock-arm 95 upon the throttle-shaft *b* is provided at its end with a pin 96, engaging longitudinal slots in the outer ends of the links 94. The arrangement is such that the shaft *b* can ordinarily be shifted in opposite directions from the engineer's platform to open and close the throttles without shifting the piston of the throttling-engine, since during such operation the pin 96 on the rock-arm 95 moves back and forth in the slots in the links 94; but when steam is admitted to the engine-cylinder *G* by the operation of the automatic throttling mechanism its piston will move forwardly and turn the throttle-shaft *b* to close the throttles. In this forward position of the engine shaft *b* is held against movement, so that the throttles cannot be opened by the engineer until he has first operated the reverse-shaft *f*, through the medium of the connecting-rod 59, to throw the cam-actuating member *E* away from the controlling-shifter *D*. When this occurs, spring 49 will restore the normal position of the controlling-arm 54 and steam will be admitted to the opposite end of the throttling-cylinder 130

G to withdraw the piston-rod *g* and links 94, so that the engineer may then open the throttles.

The reverse mechanism controlled by the movement of the rock-shaft *f* may be of any suitable construction. With a large engine, such as is usually employed for mine-hoists, it is desirable to employ a small auxiliary reversing-engine, and in the form shown the reverse-shaft *f* is provided with a rock-arm 97, as connected by a rod 98 to a rock-arm 99 on a short shaft 100, which is in turn provided with a small arm 101, connected by links 102 to the valve-stem 103 of the reverse-engine.

The reverse-engine may be of any suitable form. That shown is similar to the one set forth in a companion application filed by me March 15, 1906, Serial No. 306,116. The valve-operating shaft 17 is journaled at its ends in suitable brackets 104, fixed to the adjacent engine-frames, and carries at each end the crank-arm 18, which operates the valve mechanism for the adjacent engine by the mechanism previously described, and shown in Figs. 1 and 2. The gear 22 is fixed to a circular casing *H*, loosely mounted on the shaft. This casing comprises a head-section 105, having a peripheral flange 106, to which the opposite head-section 107 is bolted. A partition 108 (see Fig. 15) between the sections forms a segmental steam-chamber 109, within which is mounted a wing-piston *h*, that is keyed to the shaft. Steam passes or ports 109 extend radially through the section 105 and communicate at the inner ends with the longitudinal passages 110 in a sleeve 111, surrounding the shaft 17 and secured to the section 105. This sleeve extends through bearings 112 in the upper end of a standard or frame 113, mounted on the floor of the central pit in front of the engine-drum. These bearings are provided with annular channels 114, communicating, respectively, with the ends of the longitudinal passages 110 and also communicating by passages 115 with the steam-chests 116 on the outer face of the standard 113. These chests are connected by a pipe 117, and a valve in one of the chests operated by the valve-rod 103 is arranged to admit and exhaust steam or other motor fluid to and from the opposite ends of the segmental chamber 109 in the rotary engine member *H* to shift the wing-piston *h* therem, and thus shift the valve-shaft 17 and cranks 18 thereon to proper position to reverse the direction of movement of the engine. The controlling-valve for the reverse-engine is connected, as described, by suitable manually-controllable reverse-gear to the automatic throttling mechanism, so that the engineer is compelled to reverse the valve-gear before he can open the throttle-valves after the latter are closed by the operation of the automatic throttling mechanism.

The automatic throttling mechanism is de-

signed to be set so as to close the throttle valves when either car is within two or three hundred feet of the upper end of the mine-shaft, so that the lift of the car is completed by the momentum of the parts and so that the brake mechanism may be subsequently applied to promptly stop the engine and the cages or cars operated thereby. It is difficult and sometimes impossible to arrest the engine by the brake when running under a full head of steam, so that ordinarily the engineer must first close the throttles before operating the brake. In the present construction, however, the safety throttling mechanism automatically closes the throttles before it is necessary to apply the brake. The point of throttling will depend upon the weight and speed of the moving parts, and the controlling-shifters *D* therefore will be set in each particular instance in accordance with tests made to determine the proper point in the travel of the car for closing the throttles.

Means are preferably also provided for automatically applying the brake mechanism just before either car or cage reaches the end of its upward movement. The brake mechanism may be of any suitable or usual construction. In the form shown brake-bands *J* (see Fig. 1) are arranged between flanges 118 at the ends of the drum. One end of each band is fixed to a suitable bracket 119, (see Fig. 5,) mounted on the foundation beneath the drum. The other ends of the bands are connected to short arms 120 upon a brake-shaft *j*, that is journaled in the brackets 119. This shaft is centrally provided with an arm 121, upon the outer end of which is hung a weight *K* (see Fig. 1) by means of a connecting-link 122. The weight is arranged to shift vertically within a pit and to move the brake-shaft and tighten the brake-bands *J*. The weight *K* is normally upheld to relieve the tension of the brake-bands by an auxiliary brake-engine. (Shown in detail in Figs. 5 and 6.) The cylinder *L* of the brake-engine is mounted upon a shiftable frame 123, mounted on a base-plate 124 centrally upon the floor of the pit in front of the drum. The piston-rod *t* of this engine is connected to a cross-head 125, having a pin 126 extending within longitudinal slots in a pair of links 127. The forward ends of these links are pivotally connected to the upper end of an arm 128, that is mounted upon the brake-shaft *j* between the forked inner end of the weight-supporting arm 121, the arms 121 and 128 being securely connected together by bolts 129. A suitable valve within a steam-chest 130 on the under-side of the cylinder *L* is normally held in position to admit steam to the forward end of the cylinder to hold the piston-rod and parts connected thereto in position to relieve the tension on the brake-bands. For nice control of the brake-engine this valve is operated by a

float-lever or differential mechanism, and for this purpose the valve-stem 131 is connected by links 132 to a short rock-arm 134 on the end of a shaft 135. The outer end of the 5 shaft is provided with a depending rock-arm 136. The float-lever 137 is centrally pivoted to the lower end of a rock-arm 138. This rock-arm is centrally journaled upon a stud-shaft 139 on the frame of the brake-engine. 10 The upper end of the arm 138 is connected by a rod 140 to a swinging arm 141, journaled at its lower end upon the engine-frame and connected at its upper end by a link 142 to a bracket 143 on the cross-head 125 of the 15 brake-engine. The upper end of the float-lever is connected by a horizontal rod 144 to one arm of the bell-crank 145, (see Figs. 1 and 2,) mounted on a bracket 146 on the bed-plate C', beneath the engineer's platform C. 20 The other arm of the bell-crank 145 is connected by a vertical rod 147 to a suitable hand-lever on the engineer's platform C. The lower end of the float-lever 137 is connected by a jointed link to the lower end of 25 the rock-arm 136, that is connected, as previously described, to the valve of the brake-engine. The jointed link between the float-lever 137 and rock-arm 136 comprises separate sections 148 and 149, that are pivoted 30 together at their adjacent ends. By means of the differential valve-gear described the engineer can nicely control the application of the brakes in the well-known manner.

The section 148 of the jointed link is provided with a longitudinal cam-slot 150, through which extends a pin 151 upon the lower end of a rock-arm 152, that is mounted upon a rock-shaft 153. Normally the rock-arm 152 and pin 151 will be held in such position that the sections 148 and 149 of the jointed link are substantially in line, and the link-sections will shift back and forth, being held or guided in position by the pin 151. The shaft 153 is provided at each end with a 45 rock-arm 154, connected by a rod 155 to automatic stop mechanism which when either car is close to the end of its upward movement will shift the rock-shaft 153 in the direction of the arrow shown in Fig. 5. This 50 lifts the sections 148 and 149 of the jointed link and opens the valve of the brake-cylinder wide to effect the quick application of the brakes and also breaks the joint between the sections 148 and 149—that is to say, the 55 sections 148 and 149 are thrown out of line, so that they can no longer operate to shift the valve of the brake-engine. In such position the movement of the float-lever 137 will merely shift the sections 148 and 149 without moving the rock-arm 136. It is only when these sections of the jointed link are in line that the movement of the float-lever can properly control the operation of the valve of the brake-engine.

65 The rods 155 are shifted to effect the auto-

matic application of the brake by the mechanism shown in Figs. 3 and 4. The rod 155 is connected, as there shown, to a lug 156 on a U-shaped support 157. This support is mounted to slide laterally on a shaft or spindle 158, carried in a bracket 159, that is fixed to the upper edge of the bed or foundation 12 for the engine-frame and adjacent the outer end of the drum. A roller 160 is carried upon a spindle 161 between the arms of the support 157. The support 157 is held in normal position by a spring 162, (see Fig. 4,) coiled about the spindle 159 to hold the roller 160 out of line with the flange 118 on the edge of the drum. At the proper time support 157 is 75 shifted against the tension of the spring 162 to bring the roller 160 in line with the flange 118. The flange is provided at one point with a projecting cam 163, arranged to engage the roller so shift the support 157, rod 80 85 155, and shaft 153 to effect the application of the brake. Roller 160 is yielding held in position upon the spindle 161 by a spring 164, coiled about the spindle, so that the parts would not be broken if it were shifted when 90 the cam 163 on the drum was in its path of movement.

Support 157 is moved by a suitable shifter comprising a pair of arms 165, mounted on a cross-spindle 166, that is journaled in the 95 bracket 159 below and at right angles to the spindle or shaft 158. The upper ends of these arms (see Fig. 4) are provided with pins 167, engaging a grooved collar 168, connected to the support 157 of the roller 160. 100 The shifter is provided with a third arm 169, and the roller 170 is mounted upon a spindle 171, that extends between the upper end of this arm and a lug 172 upon one of the arms 165. 105

An actuator for the shifter is provided in the form of a cam - disk M, mounted upon shaft 66. This actuating - cam member is keyed to the shaft to rotate therewith, but is longitudinally shiftable thereon. It is normally held out of line with the roller 170, but is movable into line therewith and is provided on its face with a spiral cam-surface 173, that is arranged to engage the roller 170 and operate the shifter to move the roller 160 110 into line with the cam 163 upon the engine-drum A. A block m is mounted to slide upon the shaft 66 and upon a guide-rod 174, arranged above the shaft and extending between the brackets 68 and 159. The block 115 is thus held against revolution and is provided with a lip or flange 175, engaging an annular flange 176 on the hub of the disk-shaped cam member M. The block m is connected by a pair of links 177 with the upper arms 120 178 of a pair of bell-levers that are mounted upon a stud-shaft 179 at the upper end of a bracket 180, mounted on the floor of the pit. The other arms 181 of the bell-lever are connected together at their ends (see Figs. 2 and 130

3) and provided with a weight 182, that normally holds the actuating-cam member M in retracted position. A worm 183 on the shaft 66 engages the teeth of a worm-wheel 184, 5 mounted on the shaft 179 between the bell-levers. A cross-pin 185 in one of the arms of the wheel 184 is arranged to engage the arms 178 and shift the actuating-cam member M. The outer ends of the arms 181 of the bell-levers are spread apart, (see Fig. 2,) so that they will not be engaged by the pin 185.

The automatic brake-controlling mechanism described and shown in Figs 3 and 4 is duplicated at each end of the drum A, so that 15 the brake will be automatically applied at the end of the movement of the engine in either direction.

The gearing from the engine-shaft to the automatic throttling mechanism and also to 20 the automatic brake mechanism is such that the engine throttle-valves will be closed when one or the other of the cars approaches the upper end of its movement. The engineer may then apply the brakes through the medium of the brake-engine. Should he fail to 25 do so, however, the pin 185 upon the gear 184 at one side of the engine will engage the arms 178 to shift the cam member M into line with the roller 170, so that the latter in 30 turn will be moved to throw the roller 160 into line with the cam 163 on the adjacent end of the drum. The cam 163 engages the roller 160, and rock-shafts 153 and arm 152 thereon will be shifted to move the valve of 35 the brake-engine and effect the quick application of the brakes. In order that the roller 170 may properly mesh with the cam-surface or shoulder 173 on the actuating member M, it is yieldingly pressed toward 40 the cam member by a spring 186, coiled about the spindle 171.

As stated, the automatic throttling mechanism is set to close the throttle-valves when one or the other of the cages is within some 45 certain predetermined distance of the top of the mine-shaft, so that the remainder of its shift would be effected only under the momentum of the moving parts. The engineer cannot then open the throttles until he 50 has first reversed the engine. Should the momentum of the parts be insufficient to complete the travel of the car in the direction in which it was moving when the throttles were closed, a by-pass is provided leading around 55 the throttle-valves so that a small amount of steam may be admitted for slowly completing the travel of the car. This by-pass (see Figs. 16, 17, and 18) comprises elbows 187 and 188, leading from the large elbow 27 of 60 the steam-supply passage and communicating with a small pipe 189, leading upwardly through the cylinder jacketing and opening into the steam-chest 190 of the engine-cylinder 15 below the throttle-valve. A valve 65 191 for opening and closing this by-pass is

arranged within the elbow 187, and suitable means are provided for shifting the valve from the engineer's platform. The by-pass and controlling-valve is provided for each engine at opposite ends of the drum, and an operating-rod 192 for the by-pass valves extends from side to side and is connected at each end to a rock-arm 193 on the stem of the adjacent valve. The forked arm of the bell-crank 194 engages the rod 192 between a 70 pair of stops 195 thereon. This bell-crank is mounted on a bracket 196 on the bed-plate C', and its other arm is connected by a rod 197 to a suitable hand-lever on the engineer's platform C. 80

By aid of the automatic throttling and brake mechanism the hoisting-engine may be operated at high speed with little or no risk of accident.

It is obvious that numerous changes may 85 be made in the details of construction and arrangement of parts without departure from the essentials of the invention.

Having described my invention, what I claim as new, and desire to secure by Letters 90 Patent, is—

1. In hoisting-engines, the combination of engine-controlling mechanism, a brake and means driven by the engine for automatically and successively operating said controlling mechanism and said brake.

2. In hoisting-engines, the combination of engine-controlling mechanism, means driven by the engine for automatically operating said mechanism to arrest the flow of motive fluid to the engine and engine-reversing mechanism connected to said means to restore the same to normal condition.

3. In a hoisting-engine, the combination of throttling mechanism for the engine, a 105 brake therefor and means driven by the engine for automatically and successively operating said throttling mechanism and said brake.

4. In a hoisting-engine, the combination 110 of throttling mechanism, means driven by the engine for automatically operating said throttling mechanism and reversing-gear connected to restore said automatic means.

5. In a hoisting-engine, the combination 115 of throttling mechanism therefor and means driven by the engine for automatically operating said mechanism at a predetermined point.

6. In a hoisting-engine, the combination 120 of throttling mechanism therefor, an actuator driven by the engine for automatically operating said throttling mechanism at a predetermined point and an adjustable member co-operating with said actuator to vary the point of throttling.

7. In a hoisting-engine, the combination 125 of a throttle-valve therefor, actuating mechanism for said valve, means driven by the engine for operating said actuating mechanism to close said valve at a predetermined point,

a by-pass around said throttle-valve and a manually-operable valve controlling said by-pass.

8. In a hoisting-engine, the combination with a throttle-valve and brake therefor, of shifter mechanisms for said valve and brake and means driven by the engine for automatically and successively actuating said valve and brake shifter mechanisms at predetermined points.

9. In a hoisting-engine, the combination with a throttle-valve and brake therefor, of shifter mechanisms for said valve and brake, means driven by the engine for automatically actuating said shifter mechanisms to successively close said valve and apply said brake at predetermined points and means for manually actuating said shifter mechanisms.

10. In a hoisting-engine, the combination with a throttle-valve and brake therefor, of shifter mechanisms for said valve and brake, means driven by the engine for automatically actuating said shifter mechanisms to successively close said valve and apply said brake at predetermined points and engine-reversing gear connected to shift said actuating means to restore said valve-shifter mechanism.

11. In a hoisting-engine, the combination with a throttle-valve and brake therefor, of shifter mechanisms for said valve and brake, means driven by the engine for automatically actuating said shifter mechanisms to successively close said valve and apply said brake at predetermined points, a by-pass around said throttle-valve and a manually-shiftable valve for said by-pass.

12. In a hoisting-engine, the combination with a throttle-valve and brake therefor, of shifter mechanisms for said valve and brake, means driven by the engine for automatically actuating said shifter mechanisms to successively close said valve and apply said brake at predetermined points, engine-reversing gear connected to shift said actuating means to restore said valve shifter mechanism, a by-pass around said throttle-valve and a manually-controllable valve for said by-pass.

13. In a hoisting-engine, the combination with a throttle-valve therefor, of shifter mechanism for said valve, and an actuator continuously driven by the engine for operating said shifter mechanism to close said valve and reversing-gear for the engine connected to disengage said actuator and shifter mechanism.

14. In a hoisting-engine, the combination with a throttle-valve therefor, of operating mechanism for said valve, a shifter controlling said valve-operating mechanism, and an actuator continuously driven by the engine for operating said shifter, said actuator being arranged to move said shifter out of its path and to hold the same in such position.

15. In a hoisting-engine, the combination with a throttle-valve therefor, of operating mechanism for said valve, a shifter controlling said valve-operating mechanism, an actuator continuously driven by the engine for operating said shifter to close said valve at a predetermined point and means for relatively adjusting said actuator and shifter to vary the throttling-point.

16. In a hoisting-engine, the combination with a throttle-valve therefor, of operating mechanism for said valve, a shifter controlling said valve-operating mechanism, said actuator being arranged to move said shifter out of its path and hold the same in such position to close the throttle-valve at a predetermined point and manually-controllable reverse-gear connected to move said actuator and release said shifter.

17. In a hoisting-engine, the combination with a throttle-valve therefor of actuating mechanism for said valve, a spring-held shifter controlling the operation of said valve-operating mechanism, an actuator continuously driven by the engine for operating said shifter against the tension of its spring at a predetermined point and engine-reverse gear connected to move said shifter to release said spring-held shifter.

18. In a hoisting-engine, the combination with a throttle-valve and actuating mechanism therefor, of a shifter controlling the operation of said valve, a shifter-actuator, reducing gearing between the engine-shaft and said actuator for moving the same in one direction to operate said shifter at a predetermined point, and manually-controllable reverse-gear connected to move said actuator in another direction to release said shifter.

19. In a hoisting-engine, the combination with a throttle-valve and actuating mechanism therefor, of a shifter controlling the operation of said valve, a shifter-actuator, gearing for moving said actuator in opposite direction in correspondence with the movement of the engine, and reverse-gear connected to move the actuator transversely to such path of motion to release the shifter.

20. In a hoisting-engine, the combination with a throttle-valve and its actuating mechanism, of a shifter controlling the operation of said valve-actuating mechanism, a shifter-actuator, a feed-screw driven from the engine for reciprocating said actuator longitudinally, said shifter being located adjacent one end of the path of movement of said actuator to be operated thereby to close the throttle-valve at a predetermined point, and reverse-gear connected to shift said actuator in a transverse direction to release said shifter.

21. In a hoisting-engine, the combination with a throttle-valve and its actuating mechanism, of a shifter controlling the operation of said valve-actuating mechanism, a revolute actuator-cam for said shifter, gearing

- driven by the engine for rotating and reciprocating said actuator-cam, said shifter being located adjacent one end of the path of movement of said cam to be operated there-by to close the throttle at a predetermined point and reverse-gear connected to shift said cam transversely to release said shifter. 5
22. In a hoisting-engine, the combination with a throttle-valve and its actuating mechanism, of a shifter controlling the operation of said valve-actuating mechanism, a revolute cam member for actuating said shifter, a feed-screw whereon said cam member is mounted, and wherewith it is revolute, a nut 10 on said screw for reciprocating said cam member longitudinally and reverse-gear connected to shift said screw and cam member bodily in transverse direction to release said shifter. 15
23. In a hoisting-engine, the combination with a throttle-valve, and actuating mechanism therefor, of a shifter controlling the operation of said valve-actuating mechanism, an actuator driven by the engine in opposite direction for operating said shifter at predetermined points, means for disengaging said actuator and shifter and means for manually operating said valve-actuating mechanism. 20
24. In a hoisting-engine, the combination with a throttle-valve and shifter mechanism for said valve, of actuator mechanism driven in opposite direction in correspondence with the movement of the engine arranged to operate said valve-shifter mechanism at the opposite ends of its shift. 25
25. In a hoisting-engine, the combination with a throttle-valve and shifter mechanism for said valve, of actuator mechanism driven in opposite direction in correspondence with the movement of the engine and arranged to operate said valve-shifter mechanism at the opposite ends of its shift, and reverse-gear connected to move said actuator mechanism in either position to release said shifter mechanism. 30
26. In a hoisting-engine, the combination with a throttle-valve, brake and reverse-gear for said engine, of mechanism for automatically and successively closing said throttle and applying said brake at either end of the movement of said engine. 35
27. In a hoisting-engine, the combination with a throttle-valve, brake and reverse-gear for said engine, of mechanism for automatically and successively closing said throttle and applying said brake at either end of the movement of said engine, and controlling means for said reverse-gear connected to shift said mechanism to release the throttle-valve. 40
28. In a hoisting-engine, the combination with a throttle-valve, brake and reverse-gear for said engine, of shifter mechanisms for controlling said valve and said brake, actuator means driven by the engine for automatically 45
- operating said shifter mechanisms at each end of the movement thereof to successively close said valve and apply said brake at predetermined points and controlling mechanism for the reverse-gear connected to disengage said actuator means and said valve-shifter mechanism. 7c
29. In a hoisting-engine, the combination with a throttle-valve, valve-actuating mechanism and reverse-gear for the engine, of two shifters for controlling the operation of said valve-actuating mechanism, a shifter-actuator driven by the engine in opposite directions and arranged to operate said shifter at opposite ends of its shift, and controlling means for said reverse-gear connected to disengage said actuator from either of said shifters. 75
30. In a hoisting-engine, the combination with a throttle-valve, valve-actuating mechanism and reverse-gear for the engine, of two shifters for controlling the operation of said valve-actuating mechanism, a shifter-actuator normally in line with one of said shifters and driven in opposite directions by the engine, and controlling means for the reverse-gear connected to disengage said actuator from either one of said shifters and move it into line with the other of said shifters. 80
31. In a hoisting-engine, the combination with a throttle-valve, actuating mechanism therefor, and reversing-gear for the engine, of a shifter-actuator driven longitudinally in opposite directions by the engine, controlling-shifters for the valve-actuating mechanism at opposite ends of the movement of said actuator, and means for bodily moving said actuator transversely out of operative relation with one of said controlling-shifters and into line with the other of said shifters. 85
32. In a hoisting-engine, the combination with a throttle-valve and its actuating mechanism, of a controlling-shifter for said valve-actuating mechanism, a cylindrical cam member, and means for rotating said cam member and moving it longitudinally to operate said shifter at a predetermined point, said shifter having a spring-held roller and said cam member having a spiral cam-surface on its end for engaging said roller. 90
33. In a hoisting-engine, the combination with a throttle-valve and its actuating mechanism, of a controlling-shifter for said valve-actuating mechanism, a cylindrical cam member, means for rotating said cam member and moving it longitudinally to operate said shifter at a predetermined point, said shifter having a roller and said cam member having a spiral cam-surface on its end for engaging said roller and means for shifting said cam member transversely to release said shifter. 95
34. In a hoisting-engine, the combination with a throttle-valve, actuating mechanism therefor, and reverse-gear for the engine, of two connected shifters controlling said valve- 100
- 105
- 110
- 115
- 120
- 125
- 130

actuating mechanism, a shifter-actuator movable longitudinally between said shifters, operating gearing for said actuator driven from the engine, and controlling means for the reverse-gear connected to shift said actuator transversely away from one of said shifters and into line with the other of said shifters.

35. In a hoisting-engine, the combination with a throttle-valve and its actuating mechanism, a reverse-gear and an operating-engine therefor, of means driven from the engine for operating said valve-actuating mechanism to close said valve at a predetermined point and valve-controlling devices for said reverse-engine connected to restore said valve-actuating means.

36. In a hoisting-engine, the combination with a throttle-valve and its actuating mechanism, a reverse-gear and an operating-engine therefor, of a shifter controlling said valve-actuating mechanism, an actuator driven by the engine for operating said shifter to close the throttle-valve at a predetermined point and valve-controlling means for the reverse-engine connected to disengage said shifter and actuator.

37. In a hoisting-engine, the combination with a throttle-valve and its actuating mechanism, a reverse-gear and an operating-engine therefor, controlling-shifters for said valve-actuating means, a shifter-actuator, gearing for moving said actuator longitudinally between said shifters, and valve-controlling means for said reverse-engine connected to move said actuator transversely out of engagement with one of said shifters and into line with the other of said shifters.

38. In a hoisting-engine, the combination with a throttle-valve, of controlling means for automatically closing said valve at a predetermined point, means for manually controlling the movement of said valve operable independently of said automatic actuator means, the latter being arranged when operated to prevent the shift of said manual controlling means and reverse mechanism connected to move said automatic controlling means to release said manual controlling means.

39. In a hoisting-engine, the combination with a throttle-valve, of an engine for operating said throttle-valve, valve mechanism for said throttling-engine, and means driven by the hoisting-engine for automatically shifting said valve mechanism to close the throttle-valve at a predetermined point.

40. In a hoisting-engine, the combination with a throttle-valve, shifting mechanism therefor and reverse-gear for the engine, mechanism driven from the engine for automatically operating said valve-shifting mechanism to close the valve at a predetermined point, manual controlling means for said valve-shifting mechanism operable independently of said automatic mechanism, the latter, when operated, being arranged to prevent the shift of said manual controlling means and a shifter for the reverse-gear connected to move said automatic mechanism and release said manual-controlling means.

41. In a hoisting-engine, the combination with a throttle-valve, shifter mechanism for said valve and reverse-gear for the engine, of an auxiliary engine for said valve-shifter mechanism, a shifter controlling the valve of said engine, an actuator driven by the engine for operating said shifter at a predetermined point, and controlling means for said reverse-gear connected to disengage said actuator and shifter.

42. In a hoisting-engine, the combination with a throttle-valve and brake, of auxiliary engines for operating said valve and brake, valve-shifters for said auxiliary engines and actuator mechanism driven by the hoisting-engine for automatically operating said valve shifters to successively close said throttle-valve and apply said brake.

43. In a hoisting-engine, the combination with a brake, of an operating-engine for said brake, manually-controllable float-lever mechanism for said brake-engine, a jointed link connecting the float-lever to the valve of the brake-engine and automatic mechanism for shifting said joint-link at a predetermined point to operate the brake-engine and render the float-lever mechanism inoperative.

44. In a hoisting-engine, the combination with a brake, of an operating-engine for said brake, valve-shifter mechanism for the brake-engine, an actuator driven by the engine for said shifter but normally out of operative relation therewith, and means continuously driven from the engine for moving said shifter into operative relation with said actuator at a predetermined point.
